UNITED STATES PATENT OFFICE

ANTHONY G. SIEBENLIST, OF MILWAUKEE, WISCONSIN, ASSIGNOR, BY MESNE ASSIGNMENTS TO MILCOR STEEL COMPANY, OF MILWAUKEE, WISCONSIN, A CORPORATION OF DELAWARE

SCREEN

Application filed January 6, 1930. Serial No. 418,716.

This invention relates to a screen structure especially designed and adapted for use with metal window frames although also capable of other uses.

5 One of the principal objects of the present invention is to provide a screen of this character which may be constructed entirely of metal and which, while of simple construction and of light weight, is nevertheless 10 strong and durable and sufficiently stiff and rigid to retain its form and to stand up in use.

Another object of the invention is to provide a screen which is so constructed that its 15 frame may be made up of small pieces of metal and, if desired, may be constructed from the scrap metal which results from the manufacture of single piece metal window frames.

20 Another object of the invention resides in the provision of a screen which has a frame of such character as to permit of the easy assembly of the wire mesh or screening therewith and which also operates to maintain 25 the wire mesh or screen properly drawn or tightened and tensioned thereby avoiding sagging or bulging of the screen and providing a well appearing screen.

Other objects and advantages reside in 30 certain novel features of the construction, arrangement and combination of parts which will be hereinafter more fully described and particularly pointed out in the appended 35 claims, reference being had to the accompanying drawings, forming a part of this specification, and in which:

Figure 1 is a view in front elevation showing a screen embodying the present invention attached to a metal window frame;

40 Figure 2 is a view of the screen in rear elevation, the screen being shown detached from the window frame;

Figure 3 is a view in transverse section on line 3—3 of Figure 1; and

45 Figures 4 and 5 are detail sectional views taken on line 4—4 and 5—5, respectively, of Figure 2.

50 Referring to the drawings, and more particularly to Figures 1 and 3, the numeral 1 designates a metal window frame, having a

sash frame 2. The construction of the metal window frame and its sash 2 per se form no part of this invention but for a full disclosure of the structure of these parts reference is made to my copending application 55 for metal window structures, filed July 1, 1929, Serial No. 374,994. For the purpose of the present invention it is sufficient to understand that the metal window frame 1 has an inwardly directed marginal flange 3 around 60 its outer portion (see Figure 3) and this flange 3 is utilized as a support for the screen as will be hereinafter more fully described.

The screen embodying the present invention includes a rectangular metal frame designated generally at 5 and a piece or section of wire mesh or screening designated generally at 6. The frame 5 is made up of two similar frame members or sections designated generally at 7 and 8, respectively, 70 assembled in face to face and partially interfitting relations, as will hereinafter more clearly appear. The outer section 7 includes U-shaped end portions 9 and 10 and side strips 11 and 12. The U-shaped end portion 75 9 has a long leg 13 at one side and a short leg 14 at the other. The other U-shaped end portion 10 has a similar long leg designated at 15 and a similar short leg designated at 16, but the legs 15 and 16 are arranged on 80 the opposite sides of the frame from the legs 13 and 14.

The complementary inner frame member 8 is similarly constructed in that it has U-shaped end portions 17 and 18 and side strips 85 19 and 19'. The U-shaped end portion 17, which is directly behind the U-shaped end portion 9 of the front frame member 7 has a long leg 20 and a short leg 21, the long leg 20 of the rear frame member 8 being behind 90 the short leg 14 of the front frame member 7, as will be understood from a comparison of Figures 1 and 2. Similarly, the short leg 21 of the U-shaped end portion 17 of the rear frame member 8 is directly behind the long leg 13 of the front frame member 7. This organization is also carried out in connection with the lower U-shaped portions of the frame members in that the U-shaped portion 18 has a long leg 22 directly behind the 100

short leg 16 of the front frame member 7 and this U-shaped portion 18 also has a short leg 23 directly behind the long leg 15 of the front frame member 7. With this arrangement of the long and short legs of the front and rear frame members, the side strip 11 overlaps the end portion of the long leg 22 of the rear frame member. On the same side of the frame, the side strip 19 laps over the end portion of the long leg 13 of the front frame member. On the other side of the frame the side strips 12 and 19 similarly overlap the long legs 20 and 15, respectively, on the opposite ends of the frame.

As clearly shown in Figure 4, to adapt the pieces making up the frame 5 to have effective gripping engagement with the screening or mesh 6 and also to stiffen and strengthen the frame, the U-shaped end portions 9, 10, 17 and 18 and the side strips 11, 12 and 19 and 19' are provided with longitudinal corrugations or crimps C and C' which are constructed to interfit in the assembly and to grip between them the marginal portion of the screen. For holding the U-shaped end portions and side strips of the frame assembled and in gripping engagement with the screen, screws 25, 26 and 27 are provided, the screws 25 being engaged with registering screw threaded openings in the opposed end portions 9, 10, 17 and 18, the screws 26 having similar threaded engagement with the opposed side strips and the screws 27 connecting the overlapping portions of the side strips 35 and long legs of the U-shaped end portions. The screws, of course, pass directly through the wire mesh and aid in the fastening thereof.

For attaching the screen in position to the window the frame 5 is provided with openings 30 adapted to receive attaching screws 31 which are designated for threaded engagement with internally threaded openings 32 provided in the flange 3 of the window frame. When the screen is applied to the window frame, the frame 5 of the screen is held firmly against the flanges 3 by the screws 31 as shown in Figures 1 and 3.

With a screen of this construction the frame is stiff, strong and durable, is readily and easily constructed, will firmly hold the screening or mesh properly tensioned, is readily attached to or taken from the window frame, and permits of ready replacement of the screen mesh should this become necessary or desirable.

The invention claimed is:

1. A screen having a frame including separate front and rear frame members assembled in face to face relation, each comprising a U-shaped end portion having legs of different length and a pair of side strips, the side strips of one frame section overlapping the ends of the long legs of the U-shaped end portions of the other frame, screening having its margin

interposed between the frame sections and fastening devices for securing the frame sections together and clamping the screening therebetween.

2. A screen comprising a frame made up of separate front and rear frame members and having lengthwise corrugations, screening having its margin interposed between the frame members and releasable fastening device coacting with the frame members for securing them together and clamping the screening between and in direct engagement with the corrugations of both front and rear frame members.

3. A screen comprising front and rear frame members assembled in face to face relation, each of the frame members being made up of a plurality of sections of unequal length and being arranged with portions of the section of the front frame member overlapping portions of other sections of the rear frame member, means for securing the sections assembled and screening carried by the frame.

4. A screen comprising front and rear frame members assembled in face to face relation, each of the frame members being made up of a plurality of sections of unequal length and being arranged with portions of the sections of the front frame member overlapping portions of other sections of the rear frame member, screening having its margin interposed between said front and rear frame members, and means for securing said sections of said frame members together and clamping the screen therebetween.

5. A screen comprising front and rear frame members assembled in face to face relation, each of the frame members being made up of a plurality of sections of unequal length and being arranged with portions of the section of the front frame member overlapping portions of other sections of the rear frame member, screening having its margin interposed between said front and rear frame members, said frame members having corrugations adapted to interfit in the assembly to strengthen and stiffen the frame member and tension and clamp the screening, and means for securing the sections of the frame members together and for clamping the screening therebetween.

6. A screen having a frame including front and rear frame members assembled in face to face relation, each comprising a U-shaped end portion having legs of different length and a pair of side strips, the side strips of one frame section overlapping the ends of the long legs of the U-shaped end portions of the other frame, screening having its margin interposed between the frame sections, said sections of said frame members having longitudinally extending corrugations, the corrugations of the sections of the front frame member being adapted to interfit with the corrugations of the sections of the rear frame mem-

ber whereby to stiffen and strengthen the frame and to tension and clamp the screening between the frame members and fastening devices for securing said frame sections together and for clamping the screening there-
5 between, said frame having means facilitat-
ing the attachment of the screen to a window.

In witness whereof, I hereto affix my signature.

ANTHONY G. SIEBENLIST.
